UNITED STATES PATENT OFFICE.

HENRY F. A. BRUNS AND FRANCIES EUGENE ELDRIDGE, OF WAVERLY,
IOWA.

AUTOMATIC WINDMILL-REGULATOR.

SPECIFICATION forming part of Letters Patent No. 630,445, dated August 8, 1899.

Application filed February 25, 1899. Serial No. 706,797. (No model.)

To all whom it may concern:

Be it known that we, HENRY F. A. BRUNS and FRANCIES EUGENE ELDRIDGE, citizens of the United States, residing at Waverly, in the county of Bremer and State of Iowa, have invented certain new and useful Improvements in Automatic Windmill-Regulators; and we do hereby declare the following to be a full, clear, and exact description of the invention, such as will enable others skilled in the art to which it appertains to make and use the same.

Our invention relates to automatic windmill-regulators, whereby the wind-wheel is thrown into and out of operation when the water in a receptacle, pumped therein through the medium of the mill, attains or falls to a predetermined level.

The object of the invention is to so construct the mechanism that it will operate more evenly and cause less wear of the operating parts of the wheel than has heretofore been accomplished by analogous devices, to greatly improve the pawl-and-ratchet operating mechanism, and to otherwise improve the mechanism, as hereinafter fully described, and definitely pointed out in the claims.

In the accompanying drawings, wherein an embodiment of the invention is shown for the purpose of illustration, like reference-letters refer to corresponding parts in the several views.

Figure 1 is a front elevation of the device. Fig. 2 is a top plan view, and Figs. 3 and 4 are detail broken sectional views of the actuating-pawls.

Referring to the drawings, A A' represent supporting-brackets for the device, having a number of bolt-holes a, adapted to be secured in suitable position upon the framework of the mill. These brackets have elongated bottom portions B and the upwardly-extending centrally-arranged portions C. Mounted in suitable bearings therein and connecting the two brackets is a main axle or pivot D. Adapted to revolve upon this axle in the space between the brackets is a toothed segment E, secured to and preferably rigid with the plate or wheel E'. Correspondingly mounted at the tops of the central portions C of the brackets

upon an axle b is a pinion F, arranged to 50 mesh with the segment E. A fly or balance wheel F' is also mounted upon the axle b to one side of the pinion and adapted to be revolved by the segment through the medium of the pinion. The object of this balance-wheel is to cause the parts to operate slowly when the mill is thrown into and out of the wind, so as to prevent all jar and strain upon the mill and tower.

On both the front and rear faces of the plate E' are ratchet-segments H H', extending for a greater extent than the toothed segment. Also secured on the plate E' is the arm e, connected to the rod e' and adapted to be actuated with the plate in a manner hereinafter to 65 be described to throw the wheel in and out of the wind.

The mechanism for operating the segments may now be pointed out as follows: Loosely mounted upon the axle or pivot D in the rear of the wheel or plate E' is an elongated lever J, having at its outer end a slot j, adapted to receive and be held by a pin j', projecting from pump-rod K. Upon the inner surface of this lever, adapted to normally engage with 70 the ratchet-segment H', is a spring-pressed pawl h', projecting from the side of which is a lug L' for the purpose hereinafter stated. The pawl just referred to will hereinafter be referred to as the "actuating-pawl." A "re- 75 taining-pawl" h is preferably mounted on the top rear face of the forward bracket. This pawl is also spring-pressed and is normally held in engagement with the ratchet-segment H. Now to provide for the simultaneous withdrawal of both of these pawls we employ a cam-lever M, connected at its upper end to a rod m, leading to and controlled by a float in a tank of any usual construction adapted to receive the water from the pump. The cam-lever is pivoted upon a pin m' on the rear of the bracket A, projecting through a slot i in the pawl h. This pawl h is provided with a lug L, corresponding to the lug L' on the pawl h', and it is against the former that the cam 80 portion of the lever is adapted to work. At approximately the inner end of the pawl h is a guide or lug k, which is in the shape of an 85 90 95

arc of a circle and has its inturned ends facing the toothed segment and upon the outer face of which the lug L' of the operating-pawl constantly rides in its operation with the 5 pump-rod.

From the foregoing the operation of the entire mechanism may be understood. When the mill is thrown into the wind and reciprocating the pump-rod, the parts occupy the 10 positions shown in Fig. 1—that is, the arm e and the rod e' are elevated. The water-tank is supposed to be empty and the float occupying a very low position therein. Consequently through the rod m the cam-lever M 15 will be held outwardly. The cam portion of the lever operating upon the lug L will withdraw the pawl h against the tension of its spring and out of engagement with its ratchet-segment, and by reason of the constant engagement of the lug L' with the arc-shaped guide k the pawl h' will also be held out of engagement with its ratchet-segment. Now when the tank has been pumped full of water the 20 float rising therein will also raise the rod m, and, throwing the lever M inward, the cam-surface thereof is carried away from the lug L and the pawls thereby permitted to spring inwardly into engagement with their respective ratchets. The lever J, carrying the actuating-pawl, now being worked up and down by the pump-rod will engage the ratchet-segment H' and revolve the same in the direction indicated by the arrows, carrying with it in a downward direction the arm e and rod 25 e', thereby throwing the wheel out of the wind. The retaining-pawl engaging the segment H keeps the mechanism from turning backward when the actuating-cam is on the downward movement of its reciprocation. 30 The parts will then occupy the positions shown in dotted lines, Fig. 1. When the tank again becomes empty, the pawls will be released, as before described, and the arm e permitted to rise. The balance or fly wheel 35 causes the arm e to rise and fall evenly, particularly in its upward movement, so that the operating or wind wheel will be thrown into the wind gradually, thereby greatly reducing the strain and jar upon the actuating 40 parts.

While the toothed and ratchet segments and plate may be formed of separate pieces and suitably attached, yet, as clearly shown in the drawings, they are preferably cast in one piece, the ratchet-segments being formed 45 upon enlargements or raised portions x upon the respective side of the plate and the toothed segment upon the periphery thereof.

Having thus described the invention, what 50 we claim as new, and desire to secure by Letters Patent, is—

1. In a windmill-regulator, the combination with suitable brackets, regulating mechanism mounted therein connected with the wind- 55 wheel and adapted to throw the latter out

of the wind, comprising a pivoted member, means for rotating the same, and a balance or fly wheel in engagement with the pivoted member for preventing a sudden or jarring movement thereof, substantially as described. 70

2. In a windmill-regulator, the combination with suitable brackets, regulating mechanism mounted in said brackets connected with the wind-wheel and adapted to throw the latter out of the wind, comprising a movable toothed 75 plate, means for operating the same, and a balance or fly wheel geared to the toothed plate, for the purpose described.

3. In a windmill-regulator, the combination with suitable brackets, regulating mechanism mounted in said brackets, connected with the wind-wheel and adapted to throw the latter out of the wind, comprising a pivoted plate, a toothed segment on said plate, pawls and ratchets for rotating said plate, and a balance 80 or fly wheel in engagement with the toothed segment, substantially as described. 85

4. In a windmill-regulator, the combination with suitable brackets, regulating mechanism mounted in said brackets, connected to the wind-wheel and adapted to throw the same out of the wind comprising a plate pivoted in 90 said brackets, a toothed segment on the periphery of said plate, a balance or fly wheel meshing with said toothed segment, ratchet- 95 segments formed on the respective surfaces of the pivoted plate and retaining and actuating pawls for rotating the plate, substantially as described.

5. In a windmill-regulator, the combination with suitable brackets, regulating mechanism in said brackets connected to the wind-wheel and adapted to throw the same out of the wind, ratchets pivoted in said brackets, mechanism operating said ratchets comprising 100 spring-pressed pawls one retaining and the other actuating, and a cam-lever for withdrawing the pawls from engagement with the ratchets and a balance-wheel connected to the 105 regulating mechanism, substantially as described.

6. In a windmill-regulator, the combination with suitable brackets, regulating mechanism in said brackets connected to the windmill and adapted to throw the same out of the 110 wind, ratchets pivoted in said brackets, and mechanism operating said ratchets comprising a spring-pressed retaining-pawl, a spring-pressed actuating-pawl, a cam-lever engaging one of the pawls, and a sliding engagement 115 between the two pawls whereby when one is operated the other will be correspondingly operated, substantially as described.

7. In a windmill-regulator, the combination with suitable brackets, regulating mechanism in said brackets connected to the wind-wheel and adapted to throw the same out of the wind, ratchets pivotally secured in said brackets, and mechanism operating said ratchets, comprising an actuating spring-pressed 120 125 130

pawl, a lug on the side of said pawl, a spring-
pressed retaining-pawl having an arc-shaped
guide thereon upon which the lug on the ac-
tuating-pawl is adapted to ride, and a cam-
5 lever adapted to engage a lug on the side of
the retaining-pawl to simultaneously manipu-
late the pawls, substantially as described.

In testimony whereof we affix our signa-
tures in presence of two witnesses.
